CARBIDE INSERT BIT

Robert R. Blau, Scranton, Pa., assignor to Acker Drill Company, Inc., Scranton, Pa., a corporation of Pennsylvania

Filed July 28, 1967, Ser. No. 8,049

Term of patent 14 years

(Cl. D54—4)

FIG. 1

FIG. 2

FIG. 3

FIG. 1 is a perspective view of a carbide insert bit showing my new design;

FIG. 2 is a side elevational view thereof; and

FIG. 3 is a top view thereof.

The phantom line showing of a drill bit shank is for illustrative purposes only.

I claim:

The ornamental design for a carbide insert bit, as shown and described.
